UNITED STATES PATENT OFFICE.

WILLIAM A. BENSON, OF CHICAGO, ILLINOIS, ASSIGNOR TO AUTOMATIC ELECTRIC COMPANY, OF CHICAGO, ILLINOIS, A CORPORATION OF ILLINOIS.

WIRE CHIEF'S TEST CIRCUITS FOR TELEPHONE SYSTEMS.

Application filed February 17, 1921. Serial No. 445,710.

To all whom it may concern:

Be it known that I, WILLIAM A. BENSON, a citizen of the United States of America, and a resident of Chicago, Cook County, and 5 State of Illinois, have invented certain new and useful Improvements in Wire Chiefs' Test Circuits for Telephone Systems, of which the following is a specification.

The present invention relates in general to 10 wire chiefs' test circuits for telephone systems, but more especially to test circuits of this kind which are adapted for use in automatic telephone systems; and the object of the invention briefly stated is revision and 15 rearrangement of the circuits and the addition of certain new features whereby all the various tests to which a subscriber's line may be subjected can be performed accurately and with the maximum facility. The apparatus employed, and the various features of the invention will be described fully hereinafter, reference being had to the accompanying drawings, in which the system is 20 illustrated by means of the usual circuit diagrams.

Referring to the drawings, in order to enable the circuits to be readily understood the six sheets should be arranged as shown in Fig. 7. When laid out in this manner it will 25 be perceived that Figs. 1 to 4, inclusive, show the test circuits proper, together with the necessary auxiliary apparatus, which are located at the wire chief's desk; while Figs. 5 and 6 show the circuits of three automatic 30 switches known respectively as a test distributor, a test connector selector, and a test connector, which are used for connecting the test circuit to any subscriber's line which it is desired to test.

From an inspection of the first four sheets 40 of drawings it will be seen that two complete test circuits are provided. One of these, which will be referred to as a primary test circuit, extends through Figs. 3 and 4 and 45 terminates in the primary test plug at the right of Fig. 4. The other test circuit is the secondary test circuit and extends through Figs. 1 and 2 to the secondary test plug at the right of Fig. 2. Although some of the 50 testing devices and keys are duplicated in the two tests circuits, it may be stated that in general the primary test circuit is used for making the regular routine tests, and especially for all tests which require the use of 55 the volt meter, while the secondary test cir-

cuit is used for those tests which require a considerable length of time to perform, and which do not require the use of the volt meter.

To provide for connecting the test circuits 60 with subscribers' lines, which it is desired to test, the wire chief's position is equipped with a number of outgoing test trunk jacks such as the jack J, Fig. 5. The jack J is the terminal of a trunk line which extends by 65 way of the test trunk relay equipment M to the test distributor switch D. Test distributor D is a vertical and rotary switch of the well known Strowger type, having 100 sets of bank contacts arranged in 10 horizontal 70 rows, or levels. In addition to the usual operating magnets and controlling relays, the switch is provided with a side switch controlled by the well known private magnet, which is for the purpose of altering the 75 circuits after each series of controlling impulses is received. The switch circuits are shown complete, and will be described in full hereinafter.

The test connector selector E, Fig. 6, is 80 a switch of the Strowger type also, but differs from the test distributor D principally in having only a single level of bank contacts. It will be understood from this that the switch has a rotary movement 85 only, and that the vertical magnet and those parts which have to do only with the vertical movement of the switch may be omitted. It may be mentioned also that the off normal spring 113 is arranged so 90 that it will be shifted on the first rotary step of the switch rather than on a vertical step, as is usually the case. The test connector H is also a Strowger vertical and 95 rotary switch, has the full 100 contact sets, and so far as its mechanical construction is concerned is similar to the test distributor D. The side switch is omitted, however, and the circuits are very much simplified in accordance with the simpler functions which 100 the switch has to perform.

It will be understood that the subscribers' lines in the system are divided into groups of 100 lines each in accordance with the capacity of the connector switches, which 105 are ordinarily used for completing local connections. In every 100 line unit, in addition to the 10 or 12 local connectors which are ordinarily provided, there is one test connector such as the test connector H, the 110

latter connector switch being exclusively for the use of the wire chief in testing the subscribers' lines. One of the subscribers' lines of the group, to which the connector 5 H belongs, is shown at the extreme right of Fig. 6, and extends to the automatic telephone substation A. The reference character C indicates an individual line switch of the well known rotary type, which is provided for the use of the subscriber at 10 substation A in extending his line, when calling, to an idle first selector switch in the regular exchange trunking system.

The arrangement of the trunking between 15 the test switches will now be explained a little more fully. If we assume a 4 digit system of 10000 lines capacity, there will be 100 groups of connector switches, and as a test connector is provided in each of these 20 groups there will be 100 test connectors. Now, since the test distributors have 100 contact sets and are directly controlled in both their vertical and rotary movements, all of these test connectors may be reached 25 by way of the test distributors without any intervening switches. This is the usual arrangement for a straight 4 digit system. There will be perhaps three or four of the 30 test distributors such as the test distributor D, Fig. 5, which have common access to all 35 of the test connectors in the various groups. It happens quite often, however, that in systems which include a number of party lines, in addition to the individual or private lines, third selectors are inserted 40 between the second selectors and connectors in those major groups of the system which are used for the party line traffic. The party line subscribers are then called by means of five digits, instead of four, the extra digit being the third which controls 45 the operation of the third selectors in selecting the proper group of connectors. The drawing shows an arrangement of test switches which is adapted for use in a composite system of the type described, which includes both individual and party lines. The test distributors have direct access to 50 all of the test connectors which are located in the individual line connector groups, but on the particular level, or possibly levels, which are assigned to the party lines, the test distributors have access to test connector 55 selectors such as the test connector selector E, which is shown in Fig. 6. It is noted in this connection that the contacts in the party line level are not multiplied between the several test distributors, but a 60 trunk line extends from each contact set to a separate connector selector. For instance, considering the first contact set in the eighth level, if this contact set corresponds to a party line group, which we may assume to be the case, it is not multiplied 65 between the several test distributors but a

separate trunk line extends from this contact set in each test distributor to a different test connector selector. The test connector selectors with correspond to the same numbered contact sets in the test distributors have their banks connected in multiple and have common access to the test connectors in ten different connector groups.

Having described the system generally, the operation of the circuits will now be explained more in detail, and a description will first be given of the procedure followed in connecting one of the test circuits, say the primary test circuit, with a subscriber's line. Assuming that it is desired to test the line of substation A, Fig. 6, the telephone number of which is 45678, the wire chief first operates the calling device key C. D. and then inserts the primary plug in the jack of an idle outgoing test trunk, which we will assume is the test trunk shown at the left of Fig. 5. When the plug is inserted in the jack, a circuit is completed for the busy lamp L which is multiplied at other test positions, and the glowing of the busy lamps indicates to the other testers that this particular trunk is in use. When the calling device key is operated, the calling device S, Fig. 2, is connected across the tip and ring conductors of the test circuit and since these conductors have been extended to the heavy test conductors 9 and 11 of the test trunk by the insertion of the plug in the jack, the relays 31 and 33 of the test distributor D will be energized in series. These relays close a circuit for the slow acting release relay 32 which, upon energizing, grounds the conductor 10 at its armature 52, thus closing the circuit of the busy lamps at a new point. Relay 32 also breaks the release circuit at its armature 53 and at the same armature prepares a circuit for the vertical magnet 41 in the usual manner. It will be noticed that the lower winding of the electro-polarized relay 202 is included in the tip side of the line at the test circuit. Relay 202 is not operated, however, since a circuit has already been closed at the calling device key for its upper polarizing winding. The two windings are so connected that at this time their magnetizing effects oppose each other and the relay accordingly remains inoperative.

The calling device dial may now be operated in accordance with the first digit of the desired number, which is the digit 4. As a result a series of four interruptions is produced in the circuit of relays 31 and 33, and both of these relays accordingly deenergize momentarily four times. Relay 31, at each deenergization, transmits an impulse of current to the vertical magnet 41 over a path which may be traced from ground by way of armature 50 and its resting contact, armature 53 and its working contact, the winding of the slow acting series relay 34, winding of

the vertical magnet 41, and the side switch wiper 43, in first position, to battery. By the operation of the vertical magnet, the switch wipers 70-75, inclusive, are raised 6 step by step until they stand opposite the fourth level of bank contacts. Relay 34 is energized in series with the vertical magnet, and being slow acting retains its armature in operated position throughout the vertical 10 movement of the switch. In its operated position relay 34 closes circuits for the slow acting relay 36 and for the private magnet 39, which is also slow acting. The energization of relay 36 is without function at this 15 time, but the private magnet controls the usual escapement mechanism by means of which the side switch is prepared for its advance to second position. At the end of the vertical movement of the switch, the slow 20 acting relay 34 falls back and breaks the circuits of relay 36 and the private magnet 39. Upon the deenergization of the latter, the side switch wipers 42 and 43 are advanced to their second positions by the operation 25 of the escapement.

The dial of the calling device S may now be operated in accordance with the second digit of the desired number, which is the digit 5. As before a series of interruptions is produced in the circuit of relays 31 and 33, and these relays are accordingly deenergized intermittently five times. Relay 31 now sends a series of impulses to the rotary magnet 40 over a path which extends from 30 ground by way of armature 50 and its resting contact, armature 53 and its working contact, winding of relay 34, resting contact of armature 58, and the said armature, winding of the rotary magnet 40 and the side switch wiper 43, in second position, to battery. By the operation of the rotary magnet, the wipers 70-75, inclusive, are rotated step by step and are finally brought to rest in engagement with the particular contact set 35 which corresponds to the desired major, or thousands, group of lines. This contact set is assumed to be the one shown in the drawing, and comprises bank contacts 76-81, inclusive. The slow acting relay 34 is energized in series with the rotary magnet 40 the same as in the previous case and closes circuits for relay 36 and for the private magnet 39. The energization of the latter magnet adjusts the escapement in readiness to 40 permit the said switch wipers to pass to third position when it deenergizes. At the end of the rotary movement of the switch the slow acting relay 34 deenergizes and breaks the circuit of the private magnet 39 which thereupon deenergizes also and permits the side switch wipers to pass to their third position.

The operation described at the end of the preceding paragraph invariably result when a party line number is called, because of the

fact that the set of bank contacts in the test distributor, which is connected with, has its own test connector selector individual to it, and hence this set of contacts cannot be busy. However, in case a private or individual line number is called, in which case the test connector required is reached directly by way of the test distributor, it may be that such test connector is busy and in such case it is necessary to prevent the seizure of the connector at the test distributor and to give the calling wire chief a busy signal. It will be convenient to explain these operations. Now, if we assume, for example, that the particular trunk line shown at the right 60 of Fig. 5 extends to a test connector, rather than to a test connector selector and if we assume furthermore that this test connector is busy, then there will be a ground potential on the test contact 79. Under these circumstances, when the slow acting relay 34 falls back after the rotary movement of the switch is completed, a locking circuit is closed for the private magnet 39 which extends from the grounded test contact 79 by 65 way of the test wiper 73, side switch wiper 42, in second position, the lower winding of test relay 35, normally closed contact springs controlled by armature 56, and the winding of the private magnet 39 to battery. The private magnet is thus locked in energized 70 position and prevents the side switch wipers from going to their third positions. The heavy test conductors 82 and 83 are also held 75 open at contact springs controlled by the private magnet, and are thus kept disconnected from the wipers 70 and 75. The test relay 35 is energized in series with the private magnet. This relay opens the rotary magnet circuit at its armature 58, and at its 80 armature 59 connects a lead from the busy signalling machine to the lower side of the test trunk, thereby placing an audible busy signal upon the line which will be heard by the wire chief, and which will indicate to him that he has encountered a busy test connector. At the same time relay 35 closes a 85 circuit at its armature 57 for the reversing relay 30 which, upon operating, reverses the conductors 9 and 11 of the test trunk as regards their connections to the windings of 90 relays 31 and 33. By this operation the direction of current flow in the lower winding of the electropolarized relay 202 is reversed, and the said relay is accordingly 95 operated to close a circuit through the resistance 203, and thence through the lamp L² to battery. The lighting of the lamp L² at this stage of the operation gives 100 the wire chief a visual busy signal, supplementing the audible signal. He may now 105 follow either of two courses, that is, he may release the connection by removing the plug from the jack, in which case the test distributor is restored to normal as will be ex- 110

plained subsequently, or he may leave the connection up until the desired test connector shall have become idle. Assuming the latter course is followed, when the test connector is freed, ground is removed from test contact 79 and the circuit by which the test relay 35 and private magnet 39 are being held energized is broken. The private magnet accordingly deenergizes, closes the heavy test conductors through to the wipers, and permits the side switch wipers to pass to third position, and when the test relay 35 deenergizes it disconnects the audible busy signal, and also breaks the circuit of the reversing relay 30. Upon the deenergization of this relay, the direction of current flow in the conductors of the test trunk is restored to normal, and the electropolarized relay 202 is caused to retract its armature and extinguish the lamp L^2 . This notifies the wire chief that the desired test connector is now available and has been connected with, and he may, therefore, proceed to call the remaining digits.

After this digression we will now return to the establishment of the connection under consideration, and explain its further progress. By the operation of the test distributor which has been described, the connection has been extended through as far as the test connector selector E, Fig. 6. When the side switch wiper 43 of the test distributor reaches its third position, a circuit is closed for relay 37 which energizes and extends the operating circuit through to the impedance coil 38 in order to provide for further energization of the slow acting relay 34, and at the same time relay 37 prepares a point in the circuit of the test wiper 72, and also closes a bridge across the wipers 71 and 74 at armature 64. By the latter operation a circuit is completed for the windings of the line relay 100 of the test connector selector E, and the said relay is accordingly energized and completes a circuit for the slow acting release relay 101. Upon energizing in turn, relay 101 connects ground to the release trunk conductor 85, whereby the connector selector E is made busy. Relay 101 also opens a point in the circuit of the release magnet 106 at its armature 112, and at the same armature prepares a circuit for the rotary magnet 105. It will be queried why it is necessary to ground the test contact 79 to make the test connector selector E busy, inasmuch as according to the previous explanation of the trunking arrangement the test distributor D is the only switch which has access to the test connector selector E. This is a pertinent question and the answer is that if the trunking is arranged as described there is no particular utility in grounding the test contact 79 when the test connector selector is taken for use.

The provisions for grounding this test con-

tact causes no harm however, and they render it possible to use switches such as the test connector selector E in alternative trunking arrangements without change. For instance, when the testing facilities are increased the number of test distributors D will increase faster than the number of test connector selectors in any one group. Thus, the number of test connector selectors need not exceed three no matter what size the system is, but it is conceivable that the number of test distributors might be increased to six or even more. In such case there would be two test distributors having access to each of the three test connector selectors in each group.

The wire chief may now operate the dial of the calling device S in accordance with the third digit of the desired number and as a result another series of interruptions are produced in the circuit of relays 31 and 33 of the test distributor D. As before, the relay 31 sends an impulse of current, at each deenergization, through the slow acting series relay 34, and the said relay is energized and remains in operated position throughout the transmission of the third series of impulses, the same as it did during the transmission of the first and second series. Since this circuit is completed by way of the coil 38, however, no further mechanical operation of the test distributor D will take place, but relay 36 and the private magnet 39 are operated nevertheless, and the latter opens the test conductors 82 and 83 while the impulses are being received. It will be noticed that the bridge across the wipers 71 and 74 which was closed at armature 64 of relay 37 includes also the armature 51 of relay 31, and it follows, therefore, that each time relay 31 deenergizes it will open the bridge to cause the deenergization of the line relay 100 of the test connector selector E. It will be seen then that the test distributor D operates as a repeater after it has itself been operated to repeat impulses to the next switch taken for use, which in this case is the aforesaid test connector selector E.

The operation of this switch may now be described. At each deenergization of the line relay 100, responsive to the impulses which are repeated from the test distributor D, an impulse of current is transmitted to the rotary magnet 105 over a path which extends from ground by way of armature 109 and its resting contact, armature 112 and its working contact, winding of the slow acting series relay 102, armature 116 and its resting contact, winding of the rotary magnet 105, and side switch wiper 108, in its first position, to battery. By the operation of the rotary magnet 105, the wipers 130-135, inclusive, are rotated step by step and are stopped in engagement with the particular set of contacts in which is termi-

nated the trunk line which extends to the test connector in the desired hundred line group. This trunk line is assumed to be the line shown in the drawing, which terminates in bank contacts 136-141, inclusive, and extends to the test connector H. The slow acting relay 102 is energized in series with the rotary magnet 105 and remains in operated position throughout the 10 rotary movement of the switch. At its armature 114, relay 102 closes a circuit for the private magnet 104 which is energized and adjusts the escapement to permit the subsequent release of the side switch. At 15 the end of the rotary movement relay 102 falls back and breaks the circuit of the private magnet 104. Whether or not the private magnet will be energized at this time depends upon whether or not the test 20 connector H is busy. Assuming first that the connector is busy, there will be a ground potential upon the test contact 139 and when relay 102 deenergizes, a locking circuit will be established which extends from 25 ground on the test contact 139 by way of the test wiper 133, side switch wiper 107, in first position, winding of test relay 103, normally closed contact springs controlled by armature 114, and the winding of private magnet 104 to battery. Since this locking circuit includes the winding of the test relay, this relay is energized in series with the private magnet. At its armatures 115 and 118, test relay 103 opens the heavy test 30 conductors 82 and 87, at its armature 116 it breaks the rotary magnet circuit, and at 35 its armature 117 the conductor 85 is disconnected from ground and is connected instead through a low resistance to the ungrounded pole of the battery. By the latter operation a circuit is completed by way of the said conductor 85, test contact 79, test wiper 73, side switch wiper 42, in third 40 position, and the upper winding of the test relay 35 to ground. Test relay 35 is accordingly energized and at its armature 55 places an audible busy signal on the line in the direction of the wire chief's test board. At the same time, at armature 57 a circuit 50 is completed for the reversing relay 30, which operates to reverse the direction of current flow in the lower winding of the electropolarized relay 202 at the test circuit and, thus, gives the wire chief a visual 55 busy signal by lighting the lamp L². These busy signal operations are substantially the same as were described before and will be readily understood. As in the previous case, the wire chief may disconnect at once, or 60 he may wait on the line until the test connector H is cleared and becomes available for use. When this occurs, ground is disconnected from the test contact 139, the test relay 103 and the private magnet 104 of the test connector selector E are deenergized, 65 and the said test relay breaks the circuit of the test relay 35 in the test distributor D. Relay 35 then drops back, removes the audible busy signal from the line and breaks the circuit of relay 30. The deenergization 70 of the latter relay then reverses the direction of current flow in the circuit of the electropolarized relay 202 back to normal, and thus causes the lamp L² to be extinguished. 75

Returning to the test connector selector E, when the private magnet 104 deenergizes, either on the breaking of its initial energizing circuit at relay 102, or upon the breaking of its locking circuit when the selected test connector is found to be busy and eventually becomes idle, a bridge is closed across wipers 131 and 134 at armature 120. This operation completes a circuit in an obvious manner for the double wound line relay 150 of the test connector H, which energizes and at its armature 160 closes a circuit for the slow acting release relay 151. Upon energizing, the latter relay grounds the test contact 139 at its armature 161 in 90 order to make the connector H busy, and at its armature 162 opens the release magnet circuit and prepares a circuit for the vertical magnet 154. 95

The dial of the calling device S may now be operated in accordance with the next digit in the desired number, which is the digit 7. As a result of the operation of the calling device a series of seven interruptions are produced in the circuit of relays 31 and 33 at the test distributor D, and these interruptions are repeated by relay 31 into the circuit of relay 100 of the test connector selector E. Responsive to the interruptions of its circuit, relay 100 then operates to repeat a like series of interruptions into the circuit of the line relay 150 of the connector H, the bridge across the wipers 131 and 134 being opened at armature 110 every time relay 100 falls back. In response to the interruptions thus produced in its circuit, relay 150 is deenergized momentarily seven times and at each deenergization transmits a current impulse to the vertical magnet 154 over a path which may be traced from ground by way of armature 160 and its resting contact, armature 162 and its working contact, off normal springs 157 and 159, winding of slow acting series relay 152, and the winding of the vertical magnet 154 to battery. By the operation of the vertical magnet 154, wipers 170-172, inclusive, are raised step by step and are brought to rest opposite the seventh level of bank contacts. Relay 152 is energized in series with the vertical magnet, and being slow acting remains in operated position throughout the vertical movement of the switch. The operation of this relay is effective to maintain the vertical magnet circuit closed notwithstanding 110 115 120 125 130

standing the fact that the off normal springs 157—159, inclusive, are shifted, which occurs at the first upward movement of the switch shaft. At the end of the vertical 5 movement of the switch, relay 152 falls back and transfers the operating circuit to the rotary magnet 155.

The calling device may now be operated for the final digit in the desired number, 10 which is the digit 8. A series of eight interruptions is thus produced in the circuit of relays 31 and 33 of the test distributor D, and these interruptions are repeated as before into the circuit of relay 100, of the 15 test connector selector E, which in turn operates to repeat them into the circuit of the line relay 150 at the test connector H. Relay 150 is, therefore, again deenergized momentarily a plurality of times and sends a series of impulses to the rotary magnet 155 20 over a circuit which extends from ground by way of armature 160 and its resting contact, armature 162 and its working contact, off normal springs 157 and 158, armature 25 163 and its resting contact, winding of the slow acting relay 153, and the winding of the rotary magnet 155 to battery. By the operation of the rotary magnet wipers 170—172, inclusive, are rotated step by step 30 and are finally brought to rest in engagement with the particular set of bank contacts in which is terminated the line of 35 substation A, these bank contacts being indicated in the drawing by reference character 173—175, inclusive. Relay 153 is energized 40 in series with the rotary magnet 155 and being slow acting retains its armatures 164 and 165 attracted during the rotary movement and thus disconnects the wipers 170 and 172 until the switch is finished operating, when it falls back and again connects 45 up the wipers to the heavy testing conductors.

Further operations at this stage depend 50 upon whether or not the line of substation A is busy or idle. It will be recalled that the circuit of the test distributor D is such that after this switch has been operated the line relay 31 continues to send impulses to 55 the slow acting relay 34 at the same time that it repeats impulses to the switches beyond. Thus, the said relay 34 is energized not only responsive to a series of impulses intended to operate the test distributor D, 60 but also to the several series of impulses which operate the test connector selector E and the test connector H. It will be evident also that whenever relay 34 pulls up, circuits are closed for the slow acting relay 65 36 and the private magnet 39. With these facts in mind, the operations which take place, if the called line is busy, will be readily understood.

If the line is busy when connection is 70 established therewith by means of the test

connector H, as explained in the foregoing, the test wiper 171 will find a ground potential on the test contact 174 and when the slow acting relay 34 in the test distributor D falls back at the end of the final series 75 of impulses a circuit is completed for the reversing relay 30, which may be traced from the grounded test contact 174 by way of test wiper 171, conductor 169, test contact 138, test wiper 132, resting contact of armature 119 and the said armature, conductor 84, test contact 78, test wiper 72, armature 54 and its working contact, armature 55 and its resting contact, working contact of armature 62 and the said armature, armature 60 80 and its working contact (slow acting relay 36 being still in energized position), and the winding of the reversing relay 30 to battery. Upon energizing, relay 30 closes a branch of the above traced circuit which extends from armature 62 by way of the working contact of armature 65 and the said armature, armature 61 and its working contact, and the winding of the slow acting 85 relay 36 to battery. It may be explained 90 that relay 30 pulls up and closes this branch circuit before the slow acting relay 36 has had time to deenergize following the breaking of its initial energizing circuit by the falling back of slow acting relay 34, and 95 relays 30 and 36 are thus both held in operated position by the ground on the test contact 174 of the busy called line. Then relay 30 operates to reverse the direction of current flow 100 in the lower winding of the electropolarized relay 202 in the test circuit in the usual manner and this relay is, therefore, operated to light the lamp L^2 and thus give the wire chief the visual busy signal. It will be noticed, however, that no audible busy signal 105 is in this case placed on the line, and indeed it would not be practical to do this inasmuch as the heavy test conductors are now actually connected with the two line conductors of the called line. Furthermore, 110 the audible busy signal is unnecessary because the wire chief's head set is connected across the test conductors in series with the calling device, and by listening on the line he can at once ascertain whether it is engaged or not.

Finding that a conversation is going on the wire chief may, of course, release the connection and try the number again later on, or he may again operate the calling device key C. D. in order to leave the connection under the control of the electropolarized relay 202. If this latter course is followed, it will be evident that when the called line becomes idle and ground is removed 115 from the test contact 174, the circuit of relays 30 and 36 of the test distributor D will be broken and the former relay upon deenergizing, will reverse the direction of current flow in the lower winding of relay 202 120 125 130

back to its normal direction of flow. Relay 202 is thus caused to deenergize and lamp L² is extinguished, the wire chief being notified by this operation that the called line 5 has become idle.

An alternative method of holding the connection on the busy line which has an advantage in that it does not involve use of the test circuit itself will now be explained 10. Assuming that in the foregoing example where the line of substation A was called and was found to be busy, the wire chief instead of proceeding as described may depress the holding button P associated 15 with the trunk and withdraw the primary test plug from the jack J. The test circuit may then be used for testing other lines while waiting for the line of substation A to become idle. The operation of the holding 20 button P, which is of the self locking type, places ground on conductor 10, prepares a circuit for the lamp L', and closes a circuit for relay 7. Upon energizing, relay 7 closes a local circuit for relays 31 and 33 of the test 25 distributor D at armature 17, and at armatures 16 and 18 disconnects the heavy test conductors 82 and 83 from conductors 11 and 9, respectively, and connects them instead to the upper and lower windings of the battery 30 feed relay 8. It follows that as long as the receiver is off on the called line, relay 8 will remain operative and will cause the lamp L' to glow. When the receiver is hung up, relay 8 will fall back and the lamp will 35 be extinguished. It will be evident also that any operation of the switchhook or calling device at the telephone will cause the lamp to flash so that the wire chief has complete supervision over the line during 40 the time that the holding button is in depressed position.

Having explained the operations which take place when the called line is busy, we will now consider what occurs when the 45 line is idle, it being immaterial whether we consider that the line is idle when called, or becomes so some time after the connection has been established. In either case, when the slow acting relay 36 of the test 50 distributor D falls back a circuit is completed which extends from ground by way of the resting contact of armature 60 and the said armature, armature 62 and its working contact, resting contact of armature 55 and the said armature, working contact of armature 54 and the said armature, test wiper 72, test contact 78, conductor 84, armature 119 and its resting contact, test wiper 132, test contact 138, conductor 80 169, test wiper 171, test contact 174, private normal conductor 177, winding of the cut off relay 179, and the winding of the rotary or stepping magnet 180 of the line switch C to battery. By the closure of the above 85 circuit, a ground potential is placed on the

test contact 174 to make the line busy in the usual manner, and at the same time relay 179 is energized and clears the line of substation A of its normal battery and ground connections in the line switch C. 70 It may be explained at this time that relay 179 is operated only about half way because of a mechanical locking device controlled by the line relay 181 and the wipers of the line switch are not connected up. 75

Having completed the connection to the line which it is desired to test, the wire chief may now restore the calling device key C. D., thereby disconnecting the calling device S from the test circuit and again 80 closing the tip and ring conductors. When in normal position, the calling device key opens the energizing circuit of the polarizing winding of relay 202 and also closes a circuit through the sleeve of the primary test plug, which may be traced from ground through the winding of relay 201, contacts of the calling device key C. D., serially related contacts in the B. C. O. key, the conn. release key, cord reverse key, and the release key, sleeve of the primary plug, and the sleeve of jack J, winding of relay 5, and the winding of relay 6 to battery. Upon the closure of the above circuit, relays 201 85 and 5 are energized, but relay 6, which is of low resistance and which is marginally adjusted, does not pull up. Relay 201 closes the tip side of the test circuit over a path which excludes the lower winding of relay 202, and also closes a circuit for the lamp L², 90 which now becomes a supervisory lamp. Relay 5 in the outgoing trunk circuit closes a local energizing circuit for relays 31 and 33 of the test distributor D at armatures 13 and 14, at the same time disconnecting these 95 relays from the heavy test conductors 11 and 9. It will be seen now that as long as the sleeve circuit remains intact, the connection will be held by the local circuit closed by relay 5 in the outgoing trunk, 100 while the tip and ring conductors of the test circuit are extended over direct metallic conductors to the two sides of the subscriber's line, respectively. 105

If it is desired to talk to the subscriber, the ringing key may now be operated momentarily in order to ring his bell and call him to the telephone. This act simply opens the two sides of the test circuit and connects a ringing current generator in bridge thereof in the usual manner. The listening key is now thrown and also the repeating coil cut-in key R. C. C. I. By the operation of the listening key the wire chief's head set is connected across the tip and ring conductors of the test circuit in series with the condenser 215, while the listening key and the R. C. C. I. key together connect the battery feed relay 206 across the tip and ring conductors also in order 115 120 125 130

to supply talking current to the transmitter at the subscriber's telephone. The circuit of the wire chief's telephone set will be sufficiently obvious without explanation, but it may be advisable to trace the connections for the relay 206 briefly. The battery supply flows from ground by way of the upper winding of relay 206, the upper right-hand winding of repeating coil R, and through serially related contacts of the R. C. C. I. and listening keys to the normally closed tip side of the test circuit, thence by way of the heavy test conductor to the subscriber's station, and back over the ring side of the test circuit to the listening key, whence it may be traced through the lower contacts of the said key, lower contacts of the R. C. C. I. key, contacts of relay 207, contacts of relay 208, the milammeter winding of the volt-milammeter, contacts of relay 208, contacts of relay 207, contacts of the V. M. reverse key, contacts of the R. C. C. I. key, lower right-hand winding of the repeating coil R and lower winding of relay 206 to battery. When the subscriber answers his telephone the resulting current flow causes relay 206 to energize and the exchange battery is connected to conductor 205, thus shunting out the supervisory lamp L² and extinguishing it. The subscriber may now be engaged in conversation in the usual manner.

In case the wire chief is busy talking to someone else and does not wish to leave the listening key on this particular test circuit in operative position, while waiting for the called subscriber to answer, he may operate the ground key instead of the listening key. This grounds the tip side of the test circuit and affords a return path for the battery supplied through the lower winding of relay 206 to the called subscriber's transmitter when he answers. Relay 206 is then operated by means of its lower winding alone and extinguishes the supervisory lamp L² as just described. This notifies the wire chief that the subscriber has answered and he may then operate his listening key and restore the ground key.

It will be convenient now to explain how the connection is released. If it is desired to release the entire connection without withdrawing the test plug from the jack of the outgoing test trunk, the release key is operated for a short interval. This opens the sleeve circuit and causes relay 5 in the outgoing trunk to be deenergized, thus breaking the local energizing circuit for relays 31 and 33 in the test distributor D and again connecting these relays to the heavy test connectors 11 and 9, respectively.

Assuming now that all the other keys in the test circuit are in normal position, there will be no circuit closed to maintain the said relays 31 and 33 energized and they

will fall back. Relay 31 breaks the operating circuit extending to the test connector selector E, and also breaks the circuit of the slow acting release relay 32. When the latter relay falls back it closes a circuit for the release magnet 44 which restores the test distributor D to normal position in the well known manner. At the test connector selector E when the circuit of the line relay 100 is broken, this relay falls back and breaks the circuit of the slow acting release relay 101, and, upon deenergizing, the latter relay closes the circuit of the release magnet 106. The operation of release magnet 106, of course, restores the connector selector E to normal also. The line relay 100 on deenergizing breaks the circuit of the line relay 150 of the test connector H, and this switch is accordingly restored to normal by the operation of release magnet 156, whose circuit is closed in an obvious manner by the joint action of relays 150 and 151. Thus, all the test switches in use are returned to normal position and are ready to be re-operated to connect with the same or another line.

Sometimes it is desirable to release the test connector selector and the test connector without restoring the test distributor as, for example, in case it is desired to test another line in the same group. This can be accomplished by the operation of the conn. release key. When this key is operated, the exchange battery is connected by way of resistance 205 to the tip and ring sides of the test circuit simultaneously, while at the same time the sleeve circuit is opened. Relay 5 in the outgoing trunk circuit accordingly falls back, breaks the local holding circuit for relays 31 and 33 of test distributor D, and connects these relays to the heavy testing conductors. Since both sides of the test circuit are connected to the ungrounded pole of the battery, relay 33 will be held energized, but relay 31 is short circuited and will fall back. Relay 33 holds the slow acting release relay 32 energized in order to prevent the release of the test distributor D, while relay 31 breaks the operating circuit of the test connector selector E, and thereby causes the test connector selector and test connector to be released and restored to normal, as previously described. It will be observed that relay 31 closes a circuit through the slow acting relay 34, which in turn energizes, and closes a circuit for the private magnet 39. The operation of the private magnet at this time opens the heavy testing conductors and prevents the application of battery potential to other lines while the test connector selector E and the test connector H are returning their wipers to normal position. The conn. release key need be operated only for a brief interval, and after it is restored to normal the call-

ing device key C. D. may be operated for the purpose of connecting the calling device S across the test circuit to re-operate the test connector selector and the same or another test connector.

The B. C. O. key is provided to enable the wire chief to deenergize the cut off relay of a called line and permit the testing of said line in the direction of the automatic switchboard. When the B. C. O. key is operated the sleeve circuit is divided into two sections and direct ground is placed on the section which extends toward the outgoing test trunk, while the exchange battery is connected through resistance 205 to the section which includes relay 201. The grounding of the sleeve of the plug causes the marginally adjusted relay 6 to energize and the local energizing circuit for relays 31 and 33 of the test distributor D is broken at the normally closed contact springs controlled by armature 15, while at the same armature ground is connected to the winding of relay 31. It follows that relay 31 is maintained energized, while relay 33 is permitted to fall back. The deenergization of relay 33 disconnects ground from the test wiper 72 of the test distributor switch D and thus breaks the circuit of the cut off relay 179 of the line switch C. By means of the volt milammeter, the wire chief may now test the two sides of the subscriber's line for battery and ground, respectively, in a manner which will be explained subsequently, or he may connect his calling device S across the conductors of the test circuit and call out through the automatic exchange by way of the subscriber's individual line switch C.

The standard routine tests for line troubles are performed in substantially the same manner as in ordinary practice, and hence will require only a cursory discussion. Considering first the method of testing for a ground, this test may be performed either with the volt meter scales of the volt milammeter, or with the milampere scale. With all the keys in the test circuit at normal the 100,000 ohm volt meter winding of the volt milammeter is connected from the ring side of the test circuit to ground in series with the 100 volt testing battery. The circuit may be briefly traced from the ring side of the testing circuit at the R. C. C. I. key by way of contact of V. M. reverse key, contact of relay 207, contacts of relay 208, through the 100,000 ohm winding of the volt milammeter, contacts of the scale change key, contact of relay 209, contacts of the R. C. C. I. key, contacts of the F. E. M. F. key, contacts of the scale change key, and through the 80 and 20 volt batteries in series to ground. Under the above described circuit conditions, it will be seen that if there is a ground on the ring side of the line the

needle of the volt milammeter will be deflected and the deflection is read on the 120 volt scale. The tip side of the line may be tested for ground by operating the reverse key.

In case it is desired to measure the resistance of the ground with the volt milammeter according to well known methods, it is desirable to use that winding of the volt milammeter whose resistance most clearly approximates the resistance of the ground in order to secure the maximum accuracy in the result. If the ground is of relatively low resistance, therefore, it will be advisable to use either the 20,000 ohm volt meter winding, or the 1,000 ohm volt meter winding, which may be substituted for the 100,000 ohm volt meter winding by the use of the scale change key. When thrown in one direction, this key connects the 20,000 ohm winding in the circuit and when thrown in the opposite direction it connects the 1,000 ohm winding in the circuit. With the scale change key operated in either direction the 20 volt testing battery is used, and the deflection is accordingly read on the 24 volt scale.

If desired, tests for grounds may be made with the 10 ohm milammeter winding of the volt milammeter, using the 480 milampere scale. In testing for a ground on the ring side of the line in this way, the R. C. C. I. key is operated which connects the 10 ohm milammeter winding from the ring side of the line to ground in series with the lower winding of relay 206, and the regular exchange battery over a path which may be briefly pointed out as follows: from the ring side of the line at the listening key, by way of resistance 211, contacts of the R. C. C. I. key, contacts of relay 207, contacts of relay 208, 10 ohm milammeter winding, contacts of relay 208, contacts of relay 207, contacts of the V. M. reverse key, contacts of the R. C. C. I. key, lower righthand winding of repeating coil R, lower winding of relay 206 and the exchange battery to ground. With these circuit connections it will be evident that if the ring side of the line is grounded, the needle of the volt milammeter will be deflected accordingly. The tip side of the line may be tested in a similar manner by using the reverse key.

In order to test a line for a short circuit the procedure is as follows: The line is first tested for a ground to insure that it is clear in this respect, and then the tip side of the line is grounded by the operation of the ground key, after which the ring side of the line is tested for a ground, as described in the foregoing paragraphs. It will be obvious that if the line is short circuited the ground which has been placed on the tip side of the line will be detected by testing the ring side. It will be unnecessary to state that the

test may be performed with either of the volt meter scales, or with the milammeter scale.

- Continuity tests are performed according to the usual methods, depending on the normal circuit condition of the line. If the line is supposed to be electrically continuous through a bridged ringer, drop or other device, it will be tested for a short circuit, and the size or resistance of the short will indicate whether or not the circuits are in their proper condition. If there is a condenser normally included at the station on the line there, of course, will be no deflection of the volt milammeter when the line is tested for a short circuit, and the usual method of testing a line of this kind for continuity is to rapidly operate the reverse key three or four times. If the line is O. K., the charging and discharging of the condenser at the subscriber's station will cause momentary deflections or "kicks" of the volt meter needle which indicate that the circuit is intact.

Another test which is quite frequently used is the test for foreign battery on the line, which condition may be due to crosses with other circuits. In order to make this test the F. E. M. F. key is operated, which connects the 100,000 ohm winding of the volt milammeter from the ring side of the test circuit to ground over the following path: from the ring side of the test circuit at the R. C. C. I. key by way of contacts of the V. M. reverse key, contacts of relays 207 and 208, 100,000 ohm winding of the volt milammeter, contacts of the scale change key, contacts of relay 209, contacts of the R. C. C. I. key, contacts of the F. E. M. F. key, and contacts of the V. M. reverse key to ground. It will be evident that with the volt milammeter connected in the above circuit, the needle will be deflected in case there is a battery potential on the ring side of the line. If the polarity of the foreign battery is such that it gives a negative reading of the volt milammeter the V. M. reverse key is used, which would operate simply to reverse the connections to the 100,000 ohm winding of the volt milammeter without otherwise changing the circuit connections. The tip side of the line is tested for foreign battery the same way, except that the reverse key is operated.

If the line under test is found to be crossed with another telephone line, a convenient method for making accurate and specific tests of the cross is to connect the secondary testing circuit with one of the lines, while the primary testing circuit is connected with the other line. The tip and ring sides of the secondary testing circuit may now be grounded successively by means of the ground and reverse keys, while at the same time the tip and ring sides of the line at the primary testing circuit are tested for ground in the usual manner. If the two

lines are crossed the ground which is placed on one of the lines at the secondary test circuit should be picked up on the line which is under test at the primary test circuit.

The breakdown test key is used in making insulation tests. This is a special key which is illustrated diagrammatically in the drawings as comprising the rotatable shaft 223 and the two cam wheels 220, 221, and 222, each of which controls contact springs. When it is desired to test the insulation of a telephone line with which the test circuit is connected the breakdown test key is operated manually and after a moment is restored to normal. The construction of the key is such that a number of circuit changes are produced in a definite sequence as follows:

First, the contact springs controlled by cam 220 are closed, thereby completing a circuit for relays 210, 208, and 209 in series and these relays are energized. The operation of relay 210 connects the ring side of the test circuit directly to ground, while by the joint action of all three relays the tip side of the line is connected to ground through the 96,000 ohm resistance coil which is associated with the breakdown test key. The latter circuit may be traced briefly from the tip side of the test circuit at the ground key by way of contacts of relay 208, the 10 ohm milammeter winding of the volt milammeter, contacts of relay 208, contacts of relay 210, through the 96,000 ohm resistance coil and through the normally closed contact springs controlled by cam 221 to ground.

Second, the contact springs controlled by the cam wheel 221 are operated, thereby connecting the 10 ohm milammeter winding of the volt milammeter from the tip side of the line to ground in series with the 96,000 ohm resistance coil and the 200 volt battery, the circuit being briefly traceable from the tip side of the line at the ground key by way of contacts of relay 208, the 10 ohm milammeter winding, contacts of relay 208, contacts of relay 210, the 96,000 ohm resistance, the now closed contacts controlled by cam wheel 221, and the 100 volt, 80 volt and 20 volt batteries, all in series, to ground. The inclusion of the high resistance provides for gradually charging the condenser, or condensers, included in the ringing circuits at the telephone substations and thus effectively prevents the bells from tapping.

Third, the contact springs controlled by the cam wheel 222 are closed with the result that the 96,000 ohm resistance is short circuited, and the 200 volt battery is thus connected direct to the line in series with the 10 ohm milammeter winding. If there is any defect in the insulation of the line it is obvious that a deflection of the needle of

the volt milammeter will take place which will be a sufficient indication of the defective insulation.

- When the breakdown test key is released, 5 the same operations take place as were described above, except that the circuit changes take place in inverse order. Thus, on the release of the key the 96,000 ohm resistance is again connected in the circuit by 10 the separation of the contact springs controlled by the cam wheel 222; next, the contact springs controlled by cam wheel 221 are restored to normal and the 200 volt testing battery is disconnected from the circuit; 15 and finally the relays 208, 209, and 210 are restored to normal by the separation of the contact springs controlled by cam wheel 220, whereupon all the circuits will be in their original condition.
- 20 Arrangements are provided also for testing the grade of transmission on a telephone line. In order to perform this test, the wire chief will operate the R. C. C. I. key and the transmission test key. By the operation of 25 these keys the tip and ring sides of the testing circuit are connected through the windings of the repeating coil R to the upper and lower windings of the battery supply relay 206, the ring side of the line including also the 10 ohm milammeter winding of 30 the volt milammeter. At the same time the wire chief's head set is connected with the left hand windings of the repeating coil R through an artificial line arranged for a 35 certain standard grade of transmission. The wire chief may now operate the arm of the rheostat, shown just below the volt milammeter, in order to vary the current in the transmitter at the subscriber's station. 40 The quality of the telephonic transmission from such station may thus be readily determined close enough for all practical purposes.

When the system includes subscriber's stations equipped with the nickel prepayment coin boxes, it is necessary for the wire chief to be able to test the operation of these devices, and the test circuit is accordingly so equipped. These tests are usually made in 45 conjunction with a repair man at the telephone substation, who will deposit coins according to the instructions of the wire chief and observe the operation of the apparatus as the wire chief endeavors to collect or refund the deposited coins. In order to collect 50 a coin the collect key is operated momentarily, which closes a circuit for relays 208 and 209 in series. With these relays in energized position a circuit is closed from the 55 110 volt positive direct current lead (shown at the upper righthand corner of Fig. 3) which extends by way of contacts of the collect key, contacts of relay 210, contacts of 60 relay 208, through the 10 ohm milammeter winding of the volt milammeter, contacts of 65 relay 208, and thence to the tip side of the test circuit, whence the complete circuit extends over the tip side of the test circuit and the subscriber's line and through the polarized magnet at the paystation to ground. 70 The said polarized magnet is thus operated in a proper manner to collect a deposited coin in a manner which is well known. If it is desired to test the refunding operation of the paystation the refund key is operated. 75 The actuation of this key causes the energization of relays 207 and 209 in series, whereupon the 110 volt negative direct current lead is connected to the tip side of the line over a path which includes contacts of the refund and collect keys, contacts of relay 210, contacts of relay 208, the 10 ohm milammeter winding of the volt milammeter, and contacts of relay 208 to the tip side of the test circuit. Since negative current is 80 used in this instance, instead of positive current, the electropolarized magnet at the substation is operated in the opposite direction from what was formerly the case, and the deposited coin is refunded. 85

In a well known type of party line selective ringing system, an alternating current relay is provided at each substation on the line which responds to ringing current to connect the substation ringer from one side 90 of the line to ground. In order to test the proper operation of these relays, the test circuit is provided with a substation relay testing key S. S. R. T. When this key is operated a source of ringing current is connected in series with the two primary windings of the repeating coil R¹, while the secondary windings of the said repeating coil are connected across the tip and ring sides 100 of the test circuit. At the same time the tip side of the line is opened in the direction away from the line under test, but the ring side is left closed, from which it will be seen that the 100,000 ohm volt meter winding of the volt milammeter is left connected from 110 the ring side of the line to ground in series with the 100 volt testing battery, as is its normal condition. It will be clear then that if the projection of the induced ringing current out on the subscriber's line under test 115 results in the operation of the substation relay, as it should, then the connection of the ringer to ground at such substation will cause a deflection of the needle of the volt milammeter, thus indicating that the relay 120 is working properly. The operation of a substation relay, which is supposed to connect its associated ringer to the tip side of the line, may be tested in the same way except that the reverse key is used also. 125

A brief explanation will now be given of the purpose and method of using the secondary test circuit, which is shown in Figs. 1 and 2. Before proceeding it may be well to point out that while the secondary test 130

plug is normally connected with the secondary test circuit and the primary test plug with the primary test circuit, these conditions may be reversed if desired by means of 5 the cord reverse keys. Thus, the primary test plug may be connected with the secondary test circuit by means of the cord reverse key in the primary test circuit, while the secondary test plug may be connected 10 with the primary test circuit by means of the cord reverse key in the secondary test circuit. This is very convenient in case a connection is established by means of the primary testing plug for example and it is 15 found the character of the trouble on the line requires the use of some testing key in the secondary test circuit which is not duplicated in the primary test circuit. Obviously 20 in a case of this kind it will not be necessary to change the testing plug, but the proper testing circuit may be immediately associated with the testing plug which is 25 already in use merely by operating the two cord reverse keys.

25 Beginning at the end next to the secondary test plug, the release key, the conn. release key, the B. C. O. key, the C. D. key, the ringing key, the reverse key, the ground key, the monitor key, and the listening key 30 are duplicates of the like named keys in the primary testing circuit and are provided for like purposes, which have already been described. It may be stated furthermore that the sleeve circuits and the supervisory 35 circuits associated with the secondary testing plug are the same as those associated with the primary testing plug.

The howler key is used for signalling a subscriber who has left his receiver off and 40 when operated causes a high frequency induced current to be projected out over the line, which makes a sound in the receiver which is audible at some distance therefrom. Suppose, for example, that a line is 45 reported to the wire chief as being permanently busy by reason of the receiver having been left off. The wire chief will use a secondary testing circuit and by inserting the secondary test plug in the jack 50 of an outgoing test trunk he can establish connection with the line in question in the same manner as was previously explained. As soon as the line is connected with and 55 the calling device key C. D. is restored, the battery supply relay 232 is energized and shunts out the supervisory lamp L^3 , which would otherwise be lighted by the energization of relay 230 in the sleeve circuit. The 60 wire chief may now listen on the line in order to confirm the reported nature of the trouble, and will then operate the howler key. The operation of this key disconnects 65 the two leads which extend down to the primary cord reverse key, connects the left-hand windings of the repeating coil R^4 in

series with the secondary winding of repeating coil R^5 , and closes a circuit for relay 235 which includes the movable contact lever 240 in its normal position, the working contact and lower armature of relay 232, and the uppermost contact springs of the key. Upon energizing, relay 235 establishes a locking circuit for itself at its lower armature and at its upper armature prepares a circuit for relay 234. Relay 235 70 also closes a circuit by which the high speed interrupter I is connected in series with the primary winding of the induction coil or transformer R^6 . The movable contact lever 240 is now shifted from its normal position to some other position in order to include a suitable number of turns of the secondary winding of the induction coil R^6 in series with the lefthand or primary winding of the induction coil R^4 . As a 75 result of these operations a high frequency induced alternating current is transmitted over the line and through the receiver at the subscriber's station, where the subscriber is notified by the familiar tone or "howl" in his receiver that he has forgotten to hang it up. When the receiver is replaced relay 232 is deenergized and closes a circuit for relay 234, which upon energizing, establishes a locking circuit for itself and opens 80 the circuit of the interrupter I. The howler current is thus permanently disconnected regardless of whether the subscriber again removes his receiver or not. The deenergization of relay 232 also causes the supervisory 85 lamp L^3 to be lighted, which notifies the wire chief that the receiver has been replaced and he will then restore the howler key to normal.

90 It will be observed that the tip and ring 105 sides of the secondary test circuit are normally connected through the windings of the repeating coil R^4 with the windings of the battery feed relay 232. In order to disconnect the battery feed relay when the secondary test circuit is being used in conjunction 110 with the primary test circuit in testing for crosses with other lines, the R. C. C. O. key is provided. This key may also be used when the wire chief is talking on a toll 115 line, or some other kind of line, where the party at the distant end has an independent supply of transmitter battery.

120 The sounder, shown at the upper right-hand corner of Fig. 2, may be connected across the tip and ring sides of the secondary test circuit in series with the battery by means of the sounder key, and is used for a variety of purposes. For one thing it 125 is rather useful in giving the wire chief an audible indication of the reoccurrence of swinging short circuits, or grounds. Another case in which it is used frequently is when a repair man is working on a subscriber's line and is instructed to call 130

the wire chief for a test. If the sounder is left across the line it affords a convenient method by which the repair man can signal the wire chief. The sounder is also used 5 to some extent for gauging the regularity of a series of interruptions produced by a subscriber's calling device.

Tests of the subscriber's calling device, or impulse sender, however, are usually made 10 with the impulse test key. The conductors 244 and 245 associated with this key extend to the first of a series of automatic switches, and when the key is operated the tip and ring sides of the testing circuit are 15 extended by way of the said conductors, respectively, to the line relay of this switch, which may then be operated by the subscriber at the station whose calling device is to be tested. The usual procedure is for 20 the wire chief to request the subscriber to call a certain number, and if he agrees, the wire chief will immediately restore his listening key and throw the impulse test key. The wire chief will then observe the operation 25 of the switches in response to the operation of the calling device at the subscriber's station and if any trouble is detected, he will take the necessary steps to correct it.

30 The foregoing explanations while by no means exhaustive are believed to cover the tests most commonly used with sufficient particularity to enable them to be readily performed, while the apparatus has been described in sufficient detail to enable those skilled in the art to perceive the variations from prescribed methods which are possible, and to perform other similar tests which it has not been considered necessary to describe. It will be seen that a highly organized 35 system of wire chief's testing circuits has been designed which includes many new circuit arrangements and producing many new testing and operating features, all of which add very appreciably to the commercial value of such systems.

Having described my invention, what I consider to be new and desire to have protected by Letters Patent will be pointed out 50 in the appended claims.

What I claim is:

1. In a wire chief's testing system, a test 55 circuit terminating in a three conductor cord and plug, a jack ending test trunk and a series of automatic switches for extending said test circuit into connection with a subscriber's line, a calling device adapted to control said switches over the tip and ring sides of the test circuit in series, a busy and supervisory signal controlled through the sleeve of said plug and jack, and keys and associated devices in said test circuit for performing a series of tests on a connected line.

2. In a wire chief's testing system, two 60 test circuits each terminating in a manual

cord and plug and each being provided with keys and associated testing apparatus, and a cord reverse key in each test circuit whereby the two test circuits may be interchanged with respect to said plugs. 70

3. In a wire chief's testing system, a primary test circuit terminating in a manual cord and plug, keys and a voltmeter associated with said test circuit for making voltmeter tests of subscribers' lines, a secondary 75 test circuit also terminating in a manual cord and plug, keys and other devices associated with said secondary test circuit for making line tests not requiring a voltmeter, and a cord reverse key in each test circuit 80 whereby the two test circuits may be interchanged with respect to said plugs.

4. In a wire chief's testing system, two test circuits each terminating in a manual cord and plug and each being provided with keys and associated testing apparatus, an outgoing test trunk jack and a series of automatic switches whereby either test circuit may be extended into connection with a subscriber's line, and a cord reverse key in each 90 test circuit whereby the two test circuits may be interchanged with respect to said plugs. 95

5. In a wire chief's testing system, a primary test circuit terminating in a manual cord and plug, keys and a voltmeter associated with said test circuit for making voltmeter tests of subscribers' lines, a secondary test circuit also terminating in a manual cord and plug, keys and other devices associated with said secondary test circuit for making line tests not requiring a voltmeter, an outgoing test trunk jack and a series of automatic switches whereby either test circuit may be extended into connection with a subscriber's line, and a cord reverse key in each test circuit whereby the two test circuits may be interchanged with respect to said plugs. 100

6. In a wire chief's testing system, a test circuit comprising a plurality of keys and associated apparatus for testing subscribers' lines, a series of automatic switches controllable from said test circuit to connect the same with a subscriber's line, a lamp signal, means for controlling said lamp as a busy signal to notify the wire chief during the establishment of a connection that a busy switch has been encountered, and means operative in case the connection is completed for controlling said lamp as a supervisory 115 signal to notify the wire chief when the subscriber answers. 120

7. In a wire chief's testing system, a test circuit comprising a plurality of keys and associated apparatus for testing subscribers' lines, a series of automatic switches controllable from said test circuit to connect the same with a subscriber's line, means for transmitting visual and audible busy signals to the wire chief during the establishment 125 130

- of a connection to notify him that a busy switch has been encountered, means for completing the connection to the desired line whether it is busy or not, and means for giving the wire chief a visual busy signal if the line is busy.
8. In a wire chief's testing system, a test circuit comprising a plurality of keys and associated apparatus for testing subscribers' lines, a series of automatic switches controlled from said test circuit to connect the same with a subscriber's line, a test wiper in the final switch of said series for testing the line to determine whether it is busy or idle, and a test relay in a preceding switch controlled over said test wiper for giving the wire chief a busy signal.
9. In a wire chief's testing system, a test circuit comprising a plurality of keys and associated apparatus for testing subscribers' lines, a series of automatic switches controllable from said test circuit to connect the same with a subscriber's line, a test wiper in the final switch of said series for testing the line to determine whether it is busy or idle, a test relay in a preceding switch controlled over said test wiper, and means controlled by said relay for giving the wire chief a visual busy signal.
10. In a wire chief's testing system, a test circuit comprising a plurality of keys and associated apparatus for testing subscribers' lines, a series of automatic switches controllable from said test circuit to connect the same with a subscriber's line, a test relay in the first switch of said series, means controlled by said relay for giving the wire chief a busy signal, a circuit for operating said relay during the establishment of the connection in case the second switch is busy, and another circuit for operating said relay in case the third switch is busy.
11. In a wire chief's testing system, a test circuit comprising a plurality of keys and associated apparatus for testing subscribers' lines, a series of automatic switches controllable from said test circuit to connect the same with a subscriber's line, and means in said test circuit for controlling the release of said switches whereby the wire chief can release all of said switches or only part of the said switches at his option.
12. In a wire chief's testing system, a test circuit comprising a plurality of keys and associated apparatus for testing subscribers' lines, a series of automatic switches controllable from said test circuit to connect the same with a subscriber's line, means in said switches for energizing the cut off relay of the subscriber's line when the line is connected with, and means in said test circuit for deenergizing said relay while maintaining said switches in operated position.
13. An automatic trunking system in which the switches are operated exclusively under directive control and comprising test distributor switches, test connector selector switches accessible to said distributor switches, each of the latter switches being individual to one of the former, and test connector switches each of which is accessible to a plurality of said connector selector switches.
14. An automatic trunking system in which the switches are operated exclusively under directive control and comprising test distributor switches, test connectors and test connector selectors accessible to said test distributors, each test connector being accessible in common to all of said distributor switches while each test connector selector is accessible to only one of said distributor switches, and other test connector switches each of which is accessible to a plurality of said test connector selector switches.
15. In a telephone system, a manual switchboard, means including a trunk line outgoing from said board and a train of serially related automatic switches for extending a connection to a subscriber's line, a circuit for energizing the cut-off relay of said subscriber's line, said circuit including a wiper in each of said switches, and means in the first of said switches controlled from said board for opening said circuit to deenergize said cut-off relay.
16. In a telephone system, a manual switchboard, means including a trunk line outgoing from said board and a train of serially related automatic switches for extending a connection to a subscriber's line, a circuit for energizing the cut-off relay of said subscriber's line, said circuit including a wiper in each of said switches, a jack in which said trunk line terminates at said board, and a relay controlled over the sleeve of said jack for opening said circuit to deenergize said cut-off relay.
17. In a telephone system, a manual switchboard, a trunk line outgoing from said board and having two branches, a train of automatic switches controlled over the first of said branches to extend the second of said branches to a subscriber's line and a relay at the junction of said branches controlled from said board for disconnecting the said first branch.
18. In a telephone system, a manual switchboard, a trunk line outgoing from said board and having two branches, a train of automatic switches controlled over the first of said branches to extend the second of said branches to a subscriber's line, a relay in said trunk line controlled from said board for disconnecting the said first branch, and a local circuit controlled by said relay for maintaining said switches in operated position.

Signed by me at Chicago, Cook County, Illinois, this 31st day of January, 1921.

WILLIAM A. BENSON.
